UNITED STATES PATENT OFFICE.

KARTER S. MARTIN, OF TARRANT CITY, ALABAMA.

WASH-KETTLE FURNACE.

Application filed January 18, 1923. Serial No. 613,373.

To all whom it may concern:

Be it known that I, KARTER S. MARTIN, a citizen of the United States of America, residing at Tarrant City, in the county of 5 Jefferson and State of Alabama, have invented certain new and useful Improvements in Wash-Kettle Furnaces, of which the following is a specification.

My invention relates to a new and improved type of furnace for the heating of wash kettles which are customarily in the form of cast iron pots.

More particularly, the object of my invention is to design a sheet metal furnace 15 of use with any available fuel and with or without a grate, and which is designed to facilitate the kindling of the fire, the introduction of sufficient fuel to insure the requisite heat, and the utilization of the 20 heat generated in the most efficient manner.

A further object of my invention is to design a sheet metal wash kettle furnace preferably having the shape of a truncated 25 cone with a lateral fire box extension on one side and a flue connection on the other, thus enabling the fire to be kindled under and at one side of the kettle and requiring it to pass under and entirely around the 30 kettle in its flow to the flue, the furnace being adjustable to different sized kettles.

My invention further contemplates providing the fire box with a door, draft damper and other means to effectively control and regulate the fire, and also providing a removable stove top to take the place of the kettle so that the furnace can be used as a stove.

My invention further comprises the novel 40 details of construction and arrangements of parts, which in their preferred embodiment only are illustrated in the accompanying drawings, in which:

Fig. 1 is a top plan view of the furnace 45 with the wash kettle omitted.

Fig. 2 is a side elevation of Fig. 1, with the removable stove top shown preparatory to being placed in the furnace jacket top.

Fig. 3 is a cross-sectional view on the 50 line 3—3 of Fig. 1, showing the wash kettle and grate in position and the top removed.

Similar reference numerals refer to similar parts throughout the drawings.

55 I have shown my invention especially adapted for use with the usual wash ket-

tle which is in the form of a cast iron pot 1 having an out-turned top lip or rim 2 which is adapted to rest on the furnace casing or jacket 3, which is in the form 60 of a truncated cone fabricated of suitable sheet metal which can be readily and cheaply cut, bent and riveted to the shape shown and which will have ample strength for supporting the kettle. At one side of the 65 jacket I provide a lateral fire box extension 4 which is closed overhead and extends down to the bottom level of the jacket. This fire box also is preferably fabricated 70 of the same sheet metal as the jacket and has its outer end wall 5 provided with a hinged door 6 having a suitable latch 7 and below the door are a series of draft holes 8 which are controlled by a hinged damper 9 operated by a crank 10. On the 75 side of the jacket 3 opposite to the fire box I provide an opening which is enclosed by a flue connection 11, which connection has a flat top provided with a nipple 12 to receive a stack or flue pipe 13. The opening in the jacket to the flue connection is elongated horizontally and is disposed close to the top edge of the jacket so as to require the products of combustion after passing under and about the kettle to rise to 85 the top of the jacket before escaping to the flue.

I mount on the inside wall of the jacket and fire box a plurality of angled brackets 90 or clips 14 which have their upper inturned ends lying in a horizontal plane between the draft holes 8 and the lower edge of the door. This enables me to insert a grate 15 conforming in shape approximately to the horizontal cross-section through the jacket 95 and fire box but being of sufficiently smaller width and length to enable the grate to be inserted downwardly through the top opening of the jacket and dropped into place, when required. When the furnace is to be 100 operated on the ground or on a suitable fuel supporting surface, the grate, if desired, can be dispensed with, but the grate can be furnished at comparatively small expense and the furnace converted by its use for service 105 under any conditions. The fire box 4 is provided about its jacket-engaging end with an out-turned flange 16 which is riveted or bolted to the jacket 3, the lower rivets or bolts being disposed also to engage and support grate brackets, and in like manner the lower rivets or bolts 17 connecting the end 110

wall 5 with the side of the fire box 4 can be utilized to support the grate brackets. By this arrangement it is only necessary to add a single rivet or bolt below the flue 5 connection to support a great bracket at that point, and ample support will be provided for the grate without appreciable increase in cost of the furnace.

Having assembled the furnace in the manner described, the boiler kettle is set down into the open top of the jacket 3 with its top flange 2 resting on and supported by the top of the jacket and with its bottom supported sufficiently above the level of the grate to permit the fire to be thrust and burned thereunder. The fire burning in the fire box and under the kettle will produce products of combustion which rise and flow under and entirely about the kettle and pass off through the top flue opening and can be conducted off by a smoke stack or flue, if desired.

To enable the furnace to be adapted to kettles of different sizes, the jacket is formed of two half sections divided on a vertical plane and the edges 19 of the sections are given substantial overlap on each side of the furnace. The flanges are each provided with two or more vertical series of bolt or rivet holes 19 and by setting the bolts or rivets in the desired holes the jacket can be adjusted to the desired size, within prescribed limits, and the open holes 20 will all be lapped so no flame can escape there- 35 through.

When not needed for heating a wash kettle, a stove top 18 may be placed on top of the jacket to close it overhead and permit the furnace to be used as a cooking or heating stove; or the top can be used over the kettle when the latter is in service.

Though I have described with great par-

ticularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. A kettle furnace comprising a substantially cylindrical downwardly flaring metal jacket adapted to rest on the ground, a combustion chamber forming an extension at one side of said jacket and opening unobstructedly thereinto, said jacket being free of baffles or obstructions interfering with the products of combustion, a top outlet for said products of combustion at the top of said jacket on the opposite side from the combustion chamber, and a flue having an enlarged base into which said outlet opens.

2. A kettle furnace of the character described in claim 1, in which said jacket is formed in vertical half sections lapped at their meeting edges substantially midway between the outlet flue and combustion chamber and having a series of holes for the adjustment of the diameter of the jacket.

3. A kettle furnace in accordance with claim 1, in which the combustion chamber forms a continuation of the base portion of the jacket and rests therewith on the ground, there being grate supports carried by the jacket and combustion chamber, and a grate mounted thereon and extending under a kettle mounted in the jacket.

In testimony whereof I affix my signature.

KARTER S. MARTIN.
